ATTORNEY

UNITED STATES PATENT OFFICE

NORMAN H. RICKER, OF HOUSTON, TEXAS, ASSIGNOR TO HUGHES TOOL COMPANY, OF HOUSTON, TEXAS, A CORPORATION OF TEXAS

PNEUMATIC LIFT PLUNGER

Application filed October 5, 1931. Serial No. 567,076.

This invention relates to swab plungers to be employed in lifting fluid from deep wells by gas or air pressure.

Swab plungers of this character are employed within an eduction tube for the liquid extending from the surface to a suitable depth below the liquid level. The plunger, with a load of liquid above it, is lifted by air or gas pressure from the lower end of the tube to the surface and the liquid is there discharged. This operation of the plunger may be made continuous and automatic except for clogging of the plunger with paraffin and the like and ordinary wear in the apparatus. It is found that paraffin and similar material found in the oil, tends to gather and accumulate on the interior of the eduction tube and clog the progress of the plunger.

It is an object of my invention to so construct the plunger that it will remove accumulations of paraffin and the like from the tube and thus avoid the usual clogging of the plunger in its operation.

I desire to form scraping projections on the body of the plunger which will scrape foreign material from portions of the tube at each stroke of the plunger and thus prevent accumulations thereon.

In the drawing herewith Fig. 1 is a side elevation of my plunger.

Fig. 2 is a central longitudinal section through my device.

Fig. 3 is a transverse section taken on the plane 3—3 of Fig. 1.

Fig. 4 is a broken section on the plane 4—4 of Fig. 5.

Fig. 5 is a broken detail of the upper end of my improved plunger.

My plunger is not materially different from plungers heretofore used in pneumatically operated swab devices except for the scraping elements which I employ. The body 1 of the plunger is cylindrical on its outer surface except for longitudinally extending radial ridges or lands 2, shaped to closely engage the inner surface of the eduction tube—not shown. These lands are spaced apart and their ends are grooved or beveled on the inner side at 3 to provide a scraping edge 4.

The body 1 is connected at its lower end to a ring-shaped head 5 the lower portion of said ring being beveled inwardly at 6 and a removable valve seat ring 8 is fitted on the inner face of the head and held in position by the threaded engagement of the body 1 with the head. Said valve ring has a face 7 which forms a sealing seat for the valve 9.

The valve 9 is normally supported in open position by a block 10 spaced from the valve seat by legs 11. The valve support is smaller in diameter than the body 1, and the legs 11 are connected integrally therewith on the outer face of said support. The lower ends of the legs are beveled on one side, at 12, so as to cause the plunger to tend to rotate slightly as it drops downwardly and thus cause the lands 2 to change their position circumferentially of the tube at each stroke.

The head block 10 is rounded off on its lower side to obtain a stream line effect and is formed with an axial guide for the valve stem 13 which extends from the valve head 9 downwardly through the guide and projects below to contact with a stop member in its operation. The valve head 9 is seated in open position within a recess 14 in the upper end of the block 10 so that it will tend to remain open on the downward stroke of the plunger.

The ring-shaped head 5 is of the same external diameter as the body of the plunger and the lands 2 are cut thereon in the same manner as upon the plunger body. The lower ends of the lands are beveled at 4' on the ring as they are on the upper end of the plunger. This will be clear from Figs. 1 and 2.

In the operation of the plunger the lands only are in close contact with the interior of the tube and will scrape away the paraffin from the tube and will carry it to the ends of the tube where it may be scraped away at intervals or otherwise removed. A large part of the scrapings will be carried away in the current of oil discharged from the well.

By the use of this plunger the clogging of the plunger due to accumulations of paraffin and the like is largely eliminated and the

pump will operate automatically for relatively long periods of time without change.

What I claim as new is:

1. A swab plunger adapted to be moved within an eduction tube and including a cylindrical body member, a head below the same, an upwardly tapered valve seat below said body, a valve shaped to fit said seat, means to support said valve in open position below said seat, and radially projecting lands on said body adapted to engage the inner surface of said tube.
2. A swab plunger for operation within an eduction tube in wells comprising a tubular body having a plurality of spaced lands longitudinally thereof to fit against the inner surface of said eduction tube and scrape material therefrom, a support below said body and a valve on said support to close the course through said tubular body.
3. In a swab device, a plunger including a tubular body having a cylindrical outer face, spaced lands longitudinally of said plunger adapted to engage the inner surface of an eduction tube, and scrape the tube when said plunger is moved longitudinally of said tube, a lower support on said body and a valve movable on said support.

4. In a swab device, a plunger including a tubular body having a cylindrical outer face, spaced lands longitudinally of said plunger adapted to engage the inner surface of an eduction tube, the ends of said lands being beveled outwardly to bear against and scrape the tube when said plunger is moved longitudinally of said tube, a lower support on said body and a valve movable on said support.

5. In a swab device, a plunger including a tubular body, spaced lands longitudinally of said plunger adapted to engage the inner surface of an eduction tube, the end of said plunger being grooved outwardly on the interior at said lands to bevel off to form a curved cutting edge on said lands and scrape the tube when said plunger is moved longitudinally of said tube, a lower support on said body and a valve movable on said support.

6. A plunger for lifting fluid from wells, including a tubular body, a valve controlling the passage of liquid through said body, and spaced lands extending longitudinally on the outer surface of said body to contact with the interior wall of the eduction tube and scrape material therefrom.
